FABRIC TAKE-OFF MECHANISM FOR
KNITTING MACHINES

Paul Schmidt, Wyomissing, Pa., assignor to Textile Machine Works, Wyomissing, Pa., a corporation of Pennsylvania

Application September 7, 1932, Serial No. 631,976

16 Claims. (Cl. 66—149)

This invention relates to improvements in knitting machines, and more particularly to the fabric take-off mechanism therefor.

One object of the invention is to provide novel and improved take-off tension regulating mechanism which maintains constant the tension applied to the fabric being knitted, or reciprocatively moves the fabric, in accordance with movement of the knitting needles toward or away from the fabric take-off means, and which will have a smooth, positive action at all times in such manner as to prevent vibratory or jerking effects upon the fabric, and to prevent overtravel or backlash of the take-off means, particularly at the times of application thereto, or release therefrom, of the tension regulating mechanism.

A further object is the provision of take-off tension regulating mechanism which operates, upon movement of the needles toward or away from the fabric take-off means, substantially instantaneously to vary the tension exerted thereby on the fabric, regardless of the position of the take-off means, and which is effective for minute movements of the needles.

Another object is to provide tension regulating mechanism having clutch members one of which also acts as a brake on the take-off means to eliminate jerking or backlash on the fabric; the clutch members are adapted to instantly engage from any position of disengagement, and are adjustable to enable any desired degree of tension to be maintained on the fabric, or to compensate for wear of parts in use, and the time of application, or the time of release, of the tension regulating mechanism may be accurately adjusted.

The invention comprises the novel elements, features of construction and arrangement of parts in cooperative relationship as herein set forth by the following detailed description and accompanying drawings of one embodiment thereof, reference to which will make the above and other objects and attendant advantages readily apparent.

Those parts of a straight knitting machine which come more particularly into consideration in connection with this invention are shown in the accompanying drawings, in which:

Figure 1 is a partial front elevational view of one section of a knitting machine embodying the invention;

Fig. 2 is a view, parts in section, taken on the line 2—2 of Fig. 1 and looking in the direction of the arrows;

Fig. 3 is an enlarged plan view of certain parts of the tension regulating mechanism;

Fig. 4 is an enlarged side view of certain parts of the mechanism;

Fig. 5 is a view, parts in section, taken on the line 5—5 of Fig. 3 and showing the mechanism in one position of operation; and

Fig. 6 is a fragmentary plan view, taken on the line 6—6 of Fig. 2, showing certain parts of the mechanism in one operating position.

Referring to Figs. 1 and 2, the novel tension regulating mechanism is shown in operative relation with one knitting section of a full-fashioned knitting machine of the type generally known in the art as the Reading machine, the various parts and operation of which are well known and are therefore not described here in detail. The knitting section shown comprises two half sections having sets of knitting needles 7 mounted in a needle bar 8. The needles require both vertical and horizontal movement to draw the newly formed loops of the fabric through the old loops and to press the free ends of the needle beards into grooves of the needles so as to form a closed eye in order that the old loops may slip from the needles. Needle bar 8 is actuated by a bracket 9, Fig. 2, pivotally connected at 10 to a link 11 detachably connected at 12 to needle bar rocker arm or presser lever 13 pivoted on a fixed shaft 14, and provided with a roller or cam follower 15 which cooperates with a cam 16 on machine cam shaft 17. The members above described provide for periodic reciprocation of the needle bar in a horizontal direction, forwardly and rearwardly.

Pivoted secured at 18 to a needle bar bracket 19 is a needle bar lifting arm 20 clamped at one end to a rock shaft 21; a needle lever 22, which is also clamped at one end to the rock shaft, forms with arm 20 a lever fulcrumed on shaft 21, and provided with a cam roller 23 which cooperates with a rotary cam 24 on cam shaft 17 to periodically move the needle bar in a vertical direction. Anchored springs 61 and 62 connected to the lower extremities of presser lever 13 and needle lever 22, respectively, normally bias the cam rollers 15 and 23 into contact with the cams 16 and 24.

The fabric take-off device comprises a rotary shaft 25 which is operated in the well known manner by a weight (not shown) connected thereto by a rope, and on which as many fabric take-off rollers 26 are secured as there are needle bars; fabric attaching means being generally connected

with each take-off roller in the form of straps 27 provided with a welt bar, in the case of a legger, at their outer ends adapted to engage the welt 28 of the stocking fabric of web 29.

5 During the knitting process the weight rotates shaft 25 and take-off roller 26 in a clockwise direction, as viewed in Figure 2, and thus applies tension to the fabric being knitted. In order to prevent the exertion of periodic stretching strains or jerking movements on the fabric during movement of the needles 7 through their cycle of operation, and to maintain uniform tension on the fabric and produce a fabric of uniform texture, the following tension regulating mechanism is provided.

10 Referring to Figs. 4 to 6, which are enlarged views of parts of the mechanism, a circular clutch member or hardened steel roller 31, having two shoulders 32 of smaller diameter, is keyed to the reel shaft 26. Two rocking beam members 33, more clearly shown in the plan view of Fig. 3, are rotatably mounted on the shoulders 32, the rocking beam members being held in fixed parallel relation with respect to each other by stud bolts 25 34. Positioned between the ends of the rocking beam members, and rotatably mounted on the stud bolts 34, are two oppositely disposed clutch members 35 and 36 the inner ends of which have tapered surfaces 35a and 36a adapted, upon rotation of the members in opposite directions respectively about the stud bolts 34, to clutch and lock the circular member 31 in wedging engagement therewith. The outer ends of the clutch members 35 and 36 are pivotally connected to fork heads 37 and 38 adjustably secured by collars 39 and set screws 39a to operating rods 40 and 41, respectively.

15 Operating rod 41 is pivotally connected to bell-crank lever 42 by means of a stud 43 adjustable within a slot (indicated by dotted lines) in boss 44 on the bell crank lever. A tension spring 45, Fig. 4, connected at one end to a collar 46 on rod 41 and at its other end to an ear 47 on one of the rocking beam members 33, is preferably, although 20 not necessarily, employed to insure uniform and smooth release of the clutch members at the proper time during downward movement of operating rod 41. Operating rod 40 is surrounded by a helical compression spring 48 pressing at its 25 upper end against the collar 39, and at its lower end against a shoulder portion 49 of stud 50 pivotally secured to bell crank lever 42. The lower end of rod 40 extends through, and is reciprocable within, a bore through shoulder 49 of pivotally 30 mounted stud 50, the rod having an adjustable collar 51 for limiting its upward travel.

25 The bell crank lever 42 is journaled at 52, Figs. 1 and 2, to frame member 53, and has a cam follower or roller 54 normally biased by spring 55 into engagement with a rotary cam 56 on cam shaft 17. Cams 16 and 56 are of the same general configuration; as already mentioned, cam 16 reciprocates the needle bar 8 in a horizontal direction, and similar or vertical movement is imparted by cam 56, through roller 54 and bell crank lever 42, to operating rods 40 and 41, which movement brings the clutch members 35 and 36 into engagement with clutch member 31 in the following manner: Upon movement of the needles 70 in a direction away from the take-off reel 26, bell crank lever 42 is rotated in a counter-clockwise direction, as viewed in Figs. 2, 4 and 5, thus moving operating rod 41 upwardly and rotating clutch member 36 in a counter-clockwise direction, its tapered surface 36a rolling into clutching

20 or wedging engagement with roller member 31 which at this time is rotating in a clockwise direction due to the tension normally exerted on the take-off reel by the weight hereinbefore mentioned. At the instant of clutching engagement between the members 31 and 36, the rotation of the take-off reel 26 and roller 31 relative to the rocking beam members 33 is stopped, and the continued upward movement of rod 41 causes the entire rocking beam assembly to rotate in a 10 counter-clockwise direction about the shaft 25 as an axis, carrying with it the take-off reel 26 so that the reel now rotates in a reverse direction. The rotation of the bell crank lever and upward movement of the rod 41 continue during movement of the needles in a direction away from the take-off reel, thus preventing increase in the tension or strain formerly exerted on the fabric, and causing the fabric to move in the same direction and to substantially the same extent as 15 the needles.

25 At approximately the same time that movement of rod 41 has caused engagement of clutch members 31 and 36, the movement of bell crank lever 42 has resulted in a clearance between shoulder 49 on stud 50 and collar 51 on rod 40, shown in Fig. 5; rod 40 is urged upwardly by action of spring 48 and causes rotation of clutch member 35 in a clockwise direction so that its tapered surface 35a rolls into engagement with 30 roller 31. Member 35 acts to prevent rotation of roller 31 in an opposite direction with respect to the action of member 36, so that the two members 35 and 36 coact to lock roller 31 against rotation in either direction with respect to the rocking beam assembly, and thus prevent oscillating or jerking movement of the take-off reel, or overrunning of the reel in reverse direction, during application of the tension regulating mechanism. Continued movement of bell crank lever 42 40 and rotation of the rocking beam assembly cause further compression of spring 48 and further extension of the lower end of rod 40 through the shoulder 49 of stud 50.

35 Reverse movement of the needles, i. e., in a 45 direction towards the take-off reel, causes reverse movement of the bell crank lever 42 and downward movement of operating rod 41, with consequent rotation of the rocking beam assembly and take-off reel in clockwise direction, the 50 springs 45 and 48 causing the rocking beam assembly to rotate with movement of the rod 41. Upon return of the needles to normal position with respect to the fabric take-off reel, an adjustable stop 58 on one of the rocking beam 55 members 33 engages an arm 53a of frame member 53. This stops further rotation of the rocking beam assembly, and the slight remaining travel of the operating rods causes release of the clutch members, so that the tension applied to 60 the fabric is again controlled by the weight acting through the tension take-off means.

65 Clutch 35 is of the overrunning type of clutch which locks roller 31 against rotation in a counter-clockwise direction, but permits its rotation 70 in the opposite direction. Due to the pressure exerted by spring 48, however, substantial pressure is exerted between surface 35a and the adjoining contacting surface of roller 31 while the clutch member 35 is in engagement therewith. The clutch member therefore acts as a friction brake on the roller 31 during rotation of the rocking beam assembly in a clockwise direction, and the travel of rod 40 is preferably, although not necessarily, adjusted so that this braking 75

action continues until after disengagement of member 36. The braking action of member 35 minimizes or prevents jerking or back lash effects on the fabric caused by reversal of rotation of the rocking beam assembly, or due to release of the clutch 36. If desired, however, clutch 35 may be adjusted to release simultaneously with release of clutch 36.

The effective lengths of the operating rods and travel of the clutch elements may be adjusted to any desired degree of sensitivity, and to compensate for lost motion or wear on the parts, so that the regulating mechanism will cause the tension exerted on the fabric by the take-off reel to be varied, upon movement of the needles, to instantly compensate for such movement, and move the fabric in accordance with the needle movement, so that constant uniform tension is maintained on the fabric during the needle reciprocations.

The clutch members 31 and 36 permit a very small clearance, of the order of 1/1000 of an inch, to be maintained between them while in disengaged position, and the clutch members are adapted to engage or disengage in any position relative to each other, and therefore very small movements of the needles will cause engagement or disengagement of the clutch members to accurately regulate the tension applied to the fabric, and substantially instantaneously with movement of the needles. It will be understood that in speaking of varying the tension exerted on the fabric by the take-off reel, this means variation of the tension which would be applied to the fabric if the reciprocating movement of the needles were not compensated for by the tension regulating mechanism in a manner to maintain uniform tension on the fabric.

During the narrowing operation of the knitting machine, the fabric 29 must be slackened to relieve the loop pull so as to facilitate shifting of desired loops to adjacent needles, in a manner well understood in the art, and in order to put the narrowing mechanism into operation the cam shaft 17 is shifted to the right in Fig. 1. This action causes a cam follower or roller 59 (which, as more clearly shown in the plan view of Fig. 6, is disengaged in the position of Fig. 1) to engage cam 60 on cam shaft 17, which provides suitable additional motion to the lever 42 and operating rods 40 and 41 to bring about the desired slack in the fabric 29, without changing its cyclic reciprocative movement with respect to the needles.

7. A view of the contour of cam 60 is shown in Fig. 2; the roller 59 is omitted in this view more clearly to show the other cam members. In the narrowing operation, the needle bar 8 remains at rest to facilitate loop transfer by the usual transfer points, and the tension regulating mechanism causes reverse rotation of the fabric take-off reel to provide the desired slack for the loop transfers, the cam roller 54 preferably being disengaged and inoperative during this operation. Referring to Fig. 6, the cam 60 has the necessary contour and is so timed that, at the time of shifting the cam shaft 17 to the right for the narrowing process, its camming surface adjacent to roller 59 permits engagement of the roller therewith.

The illustrative embodiment specifically shown and described may obviously be further changed, modified and applied in various ways without departing from the invention herein disclosed and claimed.

I claim:

1. In a knitting machine, a reciprocatively operated set of needles for producing a knitted fabric, tension take-off means for the fabric, and means for controlling the movement of said take-off means to compensate for the reciprocating movement of the needles, comprising overrunning clutch structure actuated in accordance with movement of the needles, said structure acting as a clutch on said take-off means to relieve tension on the fabric in one direction of movement of the take-off means and exerting a braking action on the take-off means in the opposite direction of movement thereof.

2. In a knitting machine, a reciprocatively operated set of needles for producing a knitted fabric, fabric take-off means, a member rotating in correspondence with movement of said take-off means, and means for controlling the movement of said take-off means to compensate for reciprocating movement of the needles, comprising a clutch member having a tapered cam like surface positioned adjacent said rotating member and movable into direct wedging engagement with a surface of the rotating member upon movement of said needles in a predetermined direction, and means for positively moving said clutch member in both clutching and releasing directions, and brake means acting on said rotating member upon the release of said clutch member.

3. In a knitting machine, a reciprocatively operated set of needles for producing a knitted fabric, fabric take-off means, a member rotating in correspondence with movement of said take-off means, and means for controlling the movement of said take-off means to compensate for reciprocating movement of the needles, comprising a plurality of pivotally mounted clutch members rotatable into engagement with said rotating member upon movement of the needles in a predetermined direction, said clutch members simultaneously acting in opposite directions, respectively, to prevent rotation of said member in either direction with respect to the clutch members.

4. In a knitting machine, a reciprocatively operated set of needles for producing a knitted fabric, fabric take-off means, a member rotating in correspondence with movement of said take-off means, and means for controlling the movement of said take-off means to compensate for reciprocating movement of the needles, comprising a plurality of members simultaneously movable in opposite directions, respectively, from a position of disengagement into clutching engagement with said rotating member.

5. In a knitting machine, a reciprocatively operated set of needles for producing a knitted fabric, fabric take-off means, a member rotating in correspondence with movement of said take-off means, and means for controlling the movement of said take-off means to compensate for reciprocating movement of the needles, comprising a plurality of members angularly spaced about said rotating member and adapted to be simultaneously rotated in opposite directions, respectively, into clutch engagement with said rotating member.

6. In a knitting machine, a reciprocatively operable set of needles for producing a knitted fabric, rotatable take-off means for the fabric, a member adapted to be rotated in correspondence with the take-off means, and means for controlling the movement of said take-off means to compensate for reciprocating movement of the

needles, comprising a pivotally mounted clutch member positioned adjacent to said rotatable member, and having a tapered cam-like surface adapted to be moved into direct clutching engagement with the rotatable member for opposing the tension exerted by said take-off means upon movement of said needles in a predetermined direction, and means acting upon disengagement of the pivotally mounted clutch member for controlling the subsequent action of the take-off means.

7. In a knitting machine, a reciprocatively operated set of needles for producing a knitted fabric, rotatable take-off means for the fabric, a member rotatable with the take-off means in a given direction, and means for controlling the movement of said take-off means to compensate for reciprocating movement of the needles, comprising an actuating element and a member pivotally secured thereto and rotatable into direct clutching engagement with said rotating member for opposing the tension exerted by said take-off means upon movement of said needles in a predetermined direction, and means acting upon the disengagement of the pivoted member, adapted to further control the action of the take-off means.

8. In a knitting machine, a reciprocatively operated set of needles for producing a knitted fabric, fabric take-off means, a member rotating in correspondence with movement of said take-off means, and means for controlling the movement of said take-off means to compensate for reciprocating movement of the needles, comprising a clutch actuating element, a clutch member secured to said element and having a tapered cam-like surface positioned adjacent said rotating member and rotatable into direct clutching engagement with a surface of the rotating member upon movement of said needles in a predetermined direction, and means for positively moving said clutch member into both clutching and releasing positions, and brake means acting on said rotating member upon the release of said clutch member.

45 9. In a knitting machine, a reciprocatively operated set of needles for producing a knitted fabric, fabric take-off means, a member rotating in correspondence with movement of said take-off means, and means for controlling the movement of said take-off means to compensate for reciprocating movement of the needles, comprising a rotatable clutch member having a surface eccentric with respect to the axis of rotation thereof, said surface positioned adjacent said rotating member and rotatable into direct clutching engagement with a surface of said first named rotating member upon movement of said needles in a predetermined direction, and out of clutching engagement when the needles move in an opposite direction, and means effective upon the disengagement of said clutch member to control the subsequent action of the fabric take-off means.

10. In a knitting machine, a reciprocatively operated set of needles for producing a knitted fabric, a fabric take-off device for operation by means moving it in a given direction, tension means for imparting movement to said take-off device in one direction, and tension controlling means for imparting a reverse movement to said take-off device, said tension controlling means comprising an element connected to the take-off device, a pivotal lever, and means for locking the lever to said element for preventing overtravel of the take-off roll in said reverse direction.

75 11. In a knitting machine, a reciprocatively

operated set of needles for producing a knitted fabric, fabric take-off means including a clutch element rotating in accordance with movement of said take-off means, and means for controlling the movement of said take-off means to compensate for reciprocatory movement of the needles, comprising a rotatable member, a plurality of clutch elements carried by said rotatable member and angularly spaced about the axis of said member, and means for actuating the rotatable member, said means simultaneously actuating the clutch elements carried by said rotatable member into clutching engagement with a surface of the first named clutch element, thereby causing said rotatable member to actuate said take-off means in a direction to vary the tension exerted thereby on the fabric.

12. In a knitting machine, a reciprocatively operated set of needles for producing a knitted fabric, fabric take-off means, a member rotating in correspondence with movement of said take-off means, and means for controlling the movement of said take-off means to compensate for reciprocating movement of the needles, comprising a rocking lever carrying an eccentric clutch member, and means for positively actuating said eccentric clutch member into direct clutching engagement with a surface of said rotating take-off member and for causing the rocking beam to rotate said take-off member to vary the tension exerted on the fabric by said take-off means, said actuating means also positively actuating said eccentric clutch member to release it from said rotating take-off member and to operate means controlling the subsequent action of the take-off means.

13. In a knitting machine, a reciprocatively operated set of needles for producing a knitted fabric, fabric take-off means, a member rotating in correspondence with movement of said take-off means, and means for controlling the movement of said take-off means to compensate for reciprocating movement of the needles, comprising a rocking beam, pivotally mounted clutch members carried thereby and adapted to act in opposite directions relative to movement of said rotating take-off member, and means for actuating said clutch members into clutching engagement with said rotating member and for causing the rocking beam to rotate said take-off member to control the tension exerted on the fabric by said take-off means.

14. In combination, in a straight knitting machine, cam means including a shaft for operating needles and a clutch, a needle bar, a take-off reel, a circular clutch element of said clutch coaxially fixed to the reel, a walking beam pivotally coaxial with the reel, clutch members pivoted at the ends of the beam having eccentric-cam clutch faces for cooperation with the periphery of the circular clutch element, a lever carrying a follower for clutch-operating cam of said cam means and having a link-receiving end, a member pivoted on said cam follower lever and having an aperture, a link pivotally connected to one of said pivoted clutch members and to the cam follower lever at one of a selective plurality of positions on said receiving end, a link pivotally connected to the other pivoted clutch member and extending through said aperture, and a compression spring surrounding said second link and acting between the link and the apertured member.

15. In combination, in a straight knitting machine, cam means including a shaft for operating needles and a clutch, a needle bar, a take-off reel,

5 a cylindrical clutch member of said clutch coaxially fixed to the reel, a lever having portions pivotally coaxial with the reel at opposite sides of said member, a clutch element pivoted between said opposite-side lever portions having an eccentric-cam clutch face for engagement with the periphery of said member and a portion radially outwardly from the axis of said cylindrical member beyond the outer ends of said lever portions, a lever carrying a follower for a clutch operating cam of said cam means and having a link-receiving end, and a link pivotally connected to said radially-outward portion of said pivoted clutch element and to the cam-follower lever at one of a selective plurality of positions on said receiving rod.

10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280

16. In a knitting machine, a reciprocatively-operated set of needles for producing a knitted fabric, take-off means for the fabric including a portion for engagement with the fabric and a rotatable clutch element for connection to said fabric-engaging portion, and means for con-

trolling movement of the clutch element comprising an oscillatory beam pivotally movable about an axis between its ends coincident with the axis of the rotatable clutch element, a pair of clutch members pivoted one adjacent to each end of the beam for opposite pivotal movement against and from the rotatable clutch element, a pair of links pivoted at corresponding ends one to each of said pivoted clutch members, a pivotal actuating arm for said links, one of said links having adjacent to its other end a pivotal connection to said arm adjacent to the free end of the latter, said connection being adjustable along the arm, the other link having adjacent to its other end a longitudinally-slidable connection to the arm between the pivot axis and the free end of the arm, a compression spring about the latter link between the arm and the link, and a tension spring between the oscillatory beam and the other link.

20 PAUL SCHMIDT.
